UNITED STATES PATENT OFFICE.

CHARLES ALLEN CUMMINGS, OF BATTLE CREEK, MICHIGAN, ASSIGNOR TO BATTLE CREEK BOX CO., OF BATTLE CREEK, MICHIGAN.

WIREBOUND BOX.

Application filed January 25, 1921. Serial No. 439,730.

To all whom it may concern:

Be it known that I, CHARLES ALLEN CUMMINGS, a citizen of the United States, residing at Battle Creek, in the county of Calhoun and State of Michigan, have invented certain new and useful Improvements in Wirebound Boxes, of which the following is a specification.

This invention relates to improvements in 10 wire bound boxes.

The main objects of this invention are:

First, to provide in a wire bound box an improved end closure which is secure and at the same time may be readily removed.

15 Second, to provide in a box an improved end closure which may be quickly and easily put in place and remains in position even when the box or crate is only partly filled.

Further objects, and objects relating to 20 structural details, will definitely appear from the detailed description to follow.

I accomplish the objects of my invention by the devices and means described in the following specification. The invention is 25 clearly defined and pointed out in the claims.

A structure which is a preferred embodiment of my invention is clearly illustrated in the accompanying drawing, forming a 30 part of this specification, in which:

Fig. I is a perspective view of a wire bound box embodying the features of my invention.

Fig. II is a plan view of the wall portions 35 of my improved box in the flat or knock-down.

Fig. III is a top plan view of my improved box.

Fig. IV is an enlarged detail inside view 40 showing the joint for the wall panel cleats.

Fig. V is a plan view of the end cover or end closure.

Fig. VI is a perspective view of the closure locking block.

45 Fig. VII is an enlarged detail vertical section through the cover and the upper end of the box showing the manner of engaging and disengaging the closure.

Fig. VIII is a detail vertical section on a line 50 corresponding to line 8—8 of Fig. III.

Fig. IX is a detail section on a line corresponding to line 9—9 of Fig. VIII.

Fig. X is a detail vertical section on a line

corresponding to line 10—10 of Fig. I, showing the arrangement of the bottom. 55

Fig. XI is a detail vertical section corresponding to that of Fig. IX, showing a slightly modified construction.

Fig. XII is a detail vertical section taken on a line corresponding to line 12—12 of Fig. XI.

In the drawing, similar reference characters refer to similar parts throughout the several views, and the sectional views are taken looking in the direction of the little 65 arrows at the ends of the section lines.

Referring to the drawing, the body of the box is formed of the opposed pairs of wall panels 1, 1 and 2, 2. These wall panels are provided with end cleats 3 and 4 respectively, having tongues 5 at one end and slot-like mortises 6 at their other ends adapted to coact with the tongues of adjacent cleats when the box is assembled. 75

The panels are held together in the flat 75 by the wires 7, the same being applied in the well known manner of wire bound boxes. When the box is assembled the wires are twisted together as at 8.

The bottom 9 is arranged upon the bottom 80 cleats and secured by nails 10.

The cover or end closure 11 is of such width that it may be inserted and removed between the end cleats 4. The end closure 11 is provided with cleats 12 disposed thereon in a spaced relation to its ends, one of the end cleats being farther from the end of the closure than the other, as shown in Fig. V, so that the end 13 of the closure may be introduced or inserted under one of the wall cleats 3, as indicated in Fig. VII, the closure depressed and shifted longitudinally to engage its other end 14, under the opposite wall cleat 3, as shown in Fig. VIII. 90

In the embodiment shown in Figs. I and X, the closure cleats 12 are rabbeted at their ends to provide projecting tongues 15 which engage rabbet-like recesses 16 in the inner edges of the wall cleats 4 thereby supporting the cover with its ends engaged under the cleats 3. 95

To prevent the disengagement of the closure the locking block 17 is disposed between the cleat at the end 13 of the closure and the adjacent wall cleat thereby preventing longitudinal disengaging movement of 100 105

the closure. This locking block is preferably short enough so that a tool, such as a screw driver may be engaged under its end to pry it out, a nail 18 being provided for retaining it in place.

With this simple arrangement the closure is retained even though the contents, indicated at 19, do not completely fill the box.

In the modification shown in Figs. XI and 10 XII the ends of the closure cleats 20 do not interlock with the wall cleats 4 and, therefore, the cover is supported only by the nails 18 or on the contents when the box is completely filled. Structures made according to 15 this modification are quite satisfactory and are somewhat more economical to produce than the structure of Figs. I to X.

My improved box or crate is well adapted for use in lieu of barrels in the shipping of 20 fruit, vegetables and other products and in many other relations.

Having thus described my invention, what I claim as new and desire to secure by Letters Patent, is:

25 1. In a box, the combination with the side wall panels and end cleats therefor, of a removable end closure, cleats therefor having projecting tongues at their ends, said cleats being mounted on said closure in a spaced 30 relation to its ends and so that one end of the closure may be engaged under one wall cleat and the closure shifted longitudinally to engage its other end under the opposite wall cleat, the other pair of wall cleats having rabbet-like recesses in their inner edges 35 adapted to receive the projecting tongues of said closure cleats, and a locking block adapted to be disposed between one of the closure cleats and the adjacent wall cleat when the 40 other closure cleat is in engagement with the opposite wall cleat thereby preventing longitudinal disengaging movement of the closure.

2. In a box, the combination with the side wall panels and end cleats therefor, of a removable end closure, cleats therefor having projecting tongues at their ends, said cleats being mounted on said closure in a spaced 45 relation to its ends and so that one end of the closure may be engaged under one wall cleat and the closure shifted longitudinally to engage its other end under the opposite wall cleat, the other pair of wall cleats having rabbet-like recesses in their inner edges 50 adapted to receive the projecting tongues of said closure cleats, and a locking means for 55 said closure.

3. In a box, the combination with the side wall panels and cleats therefor disposed with their outer sides substantially flush with the 60 edges of the panels, of a removable end closure, cleats secured on the outer side of said closure in a spaced relation to its ends so that one end of said closure may be engaged under one wall cleat and the closure shifted 65 longitudinally to engage its other end under the opposite wall cleat with said closure cleats lying in the plane of the wall cleats engaged by said closure, and with the ends of said closure cleats at the sides of the closure whereby the closure is supported and a locking block adapted to be disposed between one of the closure cleats and the adjacent wall cleat when the other closure cleat 70 is in engagement with the opposite wall cleat 75 and secured to one of the adjacent cleats thereby preventing longitudinal disengaging movement of the closure.

In witness whereof, I have hereunto set my hand and seal in the presence of two 80 witnesses.

CHARLES ALLEN CUMMINGS. [L.S.]
